UNITED STATES PATENT OFFICE.

PEARSALL B. JACKSON, OF NEW YORK, N. Y., ASSIGNOR OF ONE-HALF TO
FREDERICK LEEDS, OF SAME PLACE.

DESIGN FOR A TOBACCO-PIPE.

SPECIFICATION forming part of Design No. 24,419, dated June 25, 1895.

Application filed May 22, 1895. Serial No. 550,273. Term of patent 7 years.

To all whom it may concern:

Be it known that I, PEARSALL B. JACKSON, a citizen of the United States, residing in New York city, in the county and State of New York, have invented and produced a new and original Design for a Smoking Device, of which the following is a full, clear, and exact description.

Reference is to be had to the accompanying drawing, in which the figure represents a perspective view of a smoking device embodying my new design.

The design relates to a smoking device; that is, to a device for use as a pipe, a cigar holder or a cigarette holder.

The leading feature of my design consists in the stem having the portion adjacent to the bowl representing an athlete's shoe and

stocking, the same appearing as if on the human foot and leg, and the bowl rising from the instep and ornamented to simulate a foot-ball.

Minor features are the stem of a reduced thickness beyond the outer end of the representation of the stocking, thus producing a shoulder at the outer end of such stocking, and the ribbed shield-like figure at the front of the stocking.

I claim—

The design for a smoking device herein shown and described.

PEARSALL B. JACKSON.
